UNITED STATES PATENT OFFICE.

SHERMAN T. ALLEN, OF LOS ANGELES, CALIFORNIA, ASSIGNOR OF ONE-HALF TO
JOSEPH H. HUNT, OF CHICAGO, ILLINOIS.

SELF-CLEANING GROUTER FOR TRACTOR-WHEELS AND THE LIKE.

1,309,006.

Specification of Letters Patent.

Patented July 8, 1919.

Application filed November 14, 1918. Serial No. 262,514.

To all whom it may concern:

Be it known that I, SHERMAN T. ALLEN, a citizen of the United States, residing at Los Angeles, in the county of Los Angeles 5 and State of California, have invented new and useful Improvements in Self-Cleaning Grouters for Tractor-Wheels and the like, of which the following is a specification.

My invention relates to self-cleaning grouters for tractor-wheels and the like, and consists of the novel features herein shown, described and claimed.

Specifically, my object is to make a self-cleaning grouter which may easily be detached and attached to the rim of a tractor wheel and to other forms of traction wheels.

A leading feature of my self-cleaning grouter is the provision of radial pipes through which the soil is continually forced, 20 the soil falling out of the pipes at the outer side of the rim, whereas in the old form of traction tread the lugs press the soil into the ground and pack it.

Another object of my invention is to provide a gripping face for traction wheels consisting of open pipes arranged radially so that they will bite and dig into the soil as the wheel revolves in a manner similar to the action of the toe and heel of a horse's 30 hoof, and so that the soil will pass through the pipes leaving practically unpacked holes in the ground.

Another object of my invention is to provide a traction face consisting of pipes arranged radially around the rim and projecting outwardly, and to mount the pipes so that they may be easily removed when worn and new pipes easily substituted.

Another object of my invention is to substitute the strength and durability of pipes for the cast-iron traction lugs heretofore in use.

Another feature of my invention consists in the novel felly clip by which the traction 45 face is easily secured to the rim of the wheel and as easily removed.

Another feature of my invention is the specific form of grouter forming the traction surface which may be cast, tumbled and 50 assembled without any machine work.

Figure 1 is a fragmentary perspective of a traction wheel equipped with a self-cleaning grouter embodying the principles of my invention.

Fig. 2 is a view analogous to Fig. 1 showing the parts from a different angle.

Fig. 3 is a fragmentary edge view showing how the grouter is secured to the wheel rim by a felly clip.

Fig. 4 is a fragmentary cross sectional detail on the lines 4-4 of Figs. 3 and 5.

Fig. 5 is a fragmentary sectional detail on the line 5-5 of Fig. 4.

Referring to the drawing in detail, the wheel rim 1 has a flat periphery 2 and flat 65 edges 3 and 4. This rim may be a part of any desired type of traction wheel and is not my invention.

The grouter 5 is adapted to fit the periphery 2 of the wheel rim 1 and a sufficient number of the grouters 5 will make a complete tread face upon the rim 1.

The main part of the grouter 5 is a casting and consists of the central portion 6 having preferably two sockets 7 to receive 75 the pipes 8 and 9; the inclined supporting walls 10 and 11 extending from the opposite sides of the central portion 6 and flaring outwardly; the feet 12, 13, 14 and 15 extending inwardly from the outer ends of 80 the outer edges of the walls 10 and 11 and bearing against the periphery 2; the flanges 16 and 17 extending outwardly from the outer edges of the walls 10 and 11 between the feet 12 and 13 and 14 and 15 respectively; and the bearings 18 and 19 formed integral with the feet 12 and 13.

The feet 14 and 15 of the grouter 5 have toes 20 and 21 to fit under the bearings 18 and 19 of the grouter 22, and in a like manner the grouter 23 has toes to fit under the bearings 18 and 19 of the grouter 5, and in arranging to apply the grouters to a wheel the patterns are made so that when a desired number of the grouters have been applied to 95 the periphery of the wheel the tread surface of the wheel will be complete. In other words, a certain number of the grouters will fit and cover the periphery of the rim of the wheel. The grouter 5 is substantially 100 the same length from the end face 24 to the end face 25 as the rim 1 from the edge 3 to the edge 4. In making the grouter 5, the pattern is constructed to core the bolt holes 26 and 27 through the bearings 18 and 19 105 and to core or make the pipe openings 28 in the sockets 7 for the pipes 8 and 9. The pipes 8 and 9 are short pieces cut from a

length of pipe of the desired size and the pipe sections are driven tightly into the openings 28 so that the pipes 8 and 9 will project substantially equal distances in radial lines outwardly from the face of the central portion 6.

The end faces of the bearings 18 and 19 are flush with the end faces 24 and 25 and are substantially in the same planes as the edges 3 and 4 of the rim 1. The felly clips 29 and 30 are placed against the end faces of the bearings 18 and 19 and against the edges 3 and 4, and carriage bolts 31 and 32 are inserted from the inner sides through the bearings 18 and 19 outwardly through the clips 29 and 30 and nuts 33 and 34 are applied to the outer ends of the bolts, so as to draw the clips 29 and 30 tightly against the bearings 18 and 19 and the edges 3 and 4. The clips 29 and 30 are L-shaped and have inturned ends 35 and 36 to engage inside of the rim 1 so as to hold the grouters securely upon the rim. The flanges 16 and 17 fit close together, as shown in Fig. 5, and the two flanges cover the space between a pair of the bearings 18 and 19.

It is obvious that the main casting 5 may be made from a simple pattern and that when the pattern is properly made the castings will fit the periphery of the rim of the wheel for which they are intended, and it is only necessary to make the castings, put the castings through a tumbler or otherwise clean the castings, place them in position upon the rim and apply the clips and bolts. When the pipes 8 and 9 are worn, or otherwise damaged, they may be readily driven out of the sockets and new pipes applied.

Heretofore in the various traction treads the gumbo and adobe soil will stick to the tread faces and fill the depressions and make a practically smooth tread. In the use of my invention the walls 10 and 11 are sharply inclined outwardly so as to make A-shaped troughs between the grouters and the gumbo, adobe and other soils, will readily drop from these troughs. The pipes 8 and 9 make teeth of the desired length which will penetrate the soil and prevent slipping, and these pipes will cut into the soil and the soil will pass upwardly through the pipes

and be discharged from their upper ends. In this way the soil is not packed by the gripping teeth as in the use of solid teeth. As the traction wheels roll along upon the surface of the ground the pipes 8 and 9 will strike the ground at an incline and leave the ground at an incline and will bite and dig into the soil in a manner similar to the action of a horse's hoof when pulling a heavy load.

Various changes may be made without departing from the spirit of my invention as claimed.

I claim:

1. A grouter for traction wheels consisting of a central portion having pipe sockets, inclined supporting walls extending outwardly from opposite sides of the central portion, feet extending outwardly from the outer sides of the inclined walls, bearings formed integral with the feet at the outer side of one wall, toes extending from the opposite feet so that the toes of one grouter will fit under the bearings of the next grouter, and means for securing the grouter to the rim of a wheel.

2. A grouter for traction wheels consisting of a central portion having pipe sockets, inclined supporting walls extending outwardly from opposite sides of the central portion, feet extending outwardly from the outer sides of the inclined walls, bearings formed integral with the feet at the outer side of one wall, toes extending from the opposite feet so that the toes of one grouter will fit under the bearings of the next grouter, means for securing the grouter to the rim of a wheel, and pipes removably mounted in the pipe sockets.

3. The combination with a wheel rim, of a series of grouter bodies adapted to fit the periphery of the rim and forming chambers opening toward both edges of the rim, and pipe sections removably mounted radially through the grouter bodies, the openings in the pipes communicating with the chambers.

In testimony whereof I have signed my name to this specification.

SHERMAN T. ALLEN.
